MOISTENING DEVICE

Herbert B. Wilkison, Borger, Tex.

Application December 4, 1934, Serial No. 755,981

3 Claims. (Cl. 91—38)

This invention relates to moistening devices.

One of the objects of the invention is to provide a moistening device particularly adaptable for moistening stacked strips wherein the wick is combined with a follower plate which serves to maintain the stacked strips in a neat pack.

Further objects of the invention are the provision of a device of the character referred to that is strong, compact and durable, very efficient in operation, that is particularly easy to assemble and disassemble to replenish the strips, that is very simple in operation and comparatively inexpensive to manufacture and use.

With the foregoing and other objects in view, the invention consists of the novel construction, combination and arrangement of parts, as will be hereinafter more specifically described and illustrated in the accompanying drawings, wherein is disclosed the preferred embodiment of the invention, but it is to be understood that changes, variations and modifications may be resorted to without departing from the spirit of the claims hereto appended.

In the drawings wherein like reference characters denote corresponding parts throughout the several views:

Fig. 1 is a top plan view of the device in accordance with the present invention showing a stack of strips associated therewith,

Fig. 2 is a sectional plan view taken substantially on line 2—2 of Fig. 3,

Fig. 3 is a detailed vertical section taken substantially on line 3—3 of Fig. 1,

Fig. 4 is a side elevation of the device in accordance with the present invention showing the guide member in open position and the hinged section of the cover in open position,

Fig. 5 is a transverse, detailed vertical section taken substantially on line 5—5 of Fig. 1,

Fig. 6 is a perspective view of the combined wick holder and follower plate with the wick removed therefrom,

Fig. 7 is an enlarged detailed sectional view of the combined follower plate and wick holder showing the wick attached thereto.

Referring to the drawings in detail, 10 indicates a substantially rectangular tank which constitutes the water chamber of the device. Over the top of the tank is a sectional cover, one of the sections 11 being fixed to the top of the tank while the other section 12 is pivoted as at 13 on its inner end to the upper portion of the tank. The hinged cover 12 closes the opening in the top of the tank by which the tank is filled with water. In closed position, the two sections

of the cover form a flat support to receive the stack 13 of strips.

The device of the present invention is illustrated in association with the stack of strips 13, each strip of which is formed with a gummed tab 14 on the inner ends thereof. These strips are particularly used in laundries, where the strip is folded around a shirt and the gummed tab secured to the free end of the strip to form a band. Although the device is shown illustrated with such strip, it is to be understood that the device may be used for many purposes where moisture is to be supplied.

In the closed end of the tank are a pair of sockets 15 which are secured at their upper ends to the fixed cover 11 and at their lower ends to the bottom 10a of the tank 10, there being apertures in the cover registering with the openings in the sockets. The chamber 15a of the sockets tapers downwardly. A flat follower plate 16 is disposed transversely across the stack of bands 13 and also across the major portion of the fixed cover 11. The crown portion 17 of a substantially U-shaped felt wick member is secured to the lower face of the follower plate 16 by a pair of anchoring pins 18 carried by the plate. The depending portions of the pins 18 are embedded in the opposite legs 19 of the wick and form stiffening elements as well as anchoring elements. Adjacent the ends of the combined follower plate and wick holder 16 are the elongated slots 20 in which slides the reduced neck 21 of the guide posts 22. The upper ends of the guide posts are flattened into caps 23 to prevent the posts from slipping out of the slots 20. These posts are free to move in the slots 20 in a horizontal direction. The guide posts 22 taper downwardly and fit movably in the sockets 15 and the combined follower plate 16 with the wick secured thereto may be completely removed from the fixed cover. In the fixed cover 11 are a pair of apertures 24 through which the legs 19 of the wick extend and the free ends of the legs extend into the water 25 in the tank.

To one end of the tank 10 is connected the guide member A which includes a flat top 26, side flanges 27, the lower edges of which rest on the fixed cover 11, and a rear wall 28. The top, side flanges and rear wall are preferably formed integral with one another. On the side flanges 27 are a pair of outset ears 29 pivoted as at 30 to the flanges of the fixed cover 11 adjacent the end of the tank. The end of the guide member A opposed to rear wall 28 is open as at 31.

In open position, the guide member A substantially encloses the one end of the stack of strips 13 and also encloses the combined follower plate 16. When the strips are resting on the 5 sectional cover as shown in Figure 3 of the drawings, the ends of the stacked strips bear evenly against the rear wall 28 of the guide member A and maintain the strips of the stack in alignment. It will also be noticed that the 10 weight of the combined follower plate and wick holder 16 bears on the stack and cooperates to hold the stack of strips in alignment. The substantially U-shaped wick straddles the area of 15 fixed cover 11 on which the strips are stacked with the crown portion 17 supplying moisture to the gummed tabs 14 as the single strips are withdrawn. The entire tank, the guide member and all parts of the invention are preferably formed of non-corrosive metal such as 20 copper so as to withstand water without deteriorations.

Having described my invention, what I claim is:

1. A moistening device comprising a tank 25 including a cover and constituting a water chamber, a moistening wick straddling a certain area of the cover and having a portion thereof extending through the cover into the water chamber, said wick movable with respect to the cover and adapted to embrace a stack of strips, having gummed tabs, a follower plate movably supported by the cover and the portion of the wick 30

straddling the cover attached to the follower plate.

2. A moistening device comprising a tank including a cover and constituting a water chamber, a moistening wick straddling a certain area 5 of the cover and having a portion thereof extending through the cover into the water chamber, said wick movable with respect to the cover and adapted to embrace a stack of strips, having gummed tabs, a follower plate movably supported by the cover and the portion of the wick 10 straddling the cover attached to the follower plate, and a guide member hinged to one end of the tank for retaining the aforesaid stack of strips in aligned relation. 15

3. A moistening device comprising a tank including a sectional apertured cover and constituting a water chamber, one of said sections pivoted to the tank to form a filling opening, a combined follower plate and wick holder carrying movable guide posts at the ends thereof depending into certain of the apertures in the cover, a substantially U-shaped wick having the crown portion secured to an intermediate portion of the plate and the legs thereof extending into apertures of the cover plate, said moistening wick adapted to straddle a stack of strips formed with gummed tabs, that rest on the cover, and a guide member hinged to the tank 20 for retaining the aforesaid stack of strips in 25 aligned relation. 30

HERBERT B. WILKISON.
